US00D948179S

(12) United States Design Patent (10) Patent No.: US D948,179 S
(45) Date of Patent: * Apr. 12, 2022

(54) SHOE

(71) Applicant: YVES SAINT LAURENT, Paris (FR)

(72) Inventor: Anthony Vaccarello, Paris (FR)

(73) Assignee: YVES SAINT LAURENT, Paris (FR)

() Term: 15 Years

(21) Appl. No.: 29/727,850

(22) Filed: Mar. 13, 2020

(30) Foreign Application Priority Data

Oct. 18, 2019 (EM) 007055660-0001

(57) CLAIM

The ornamental design for a shoe, as shown and described.

DESCRIPTION

FIG. 1 is a perspective view of a shoe showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the shoe shown in broken lines represent thread stitching and do form a part of the claimed design.
